UNITED STATES PATENT OFFICE.

WILLIAM OST, OF NEWARK, NEW JERSEY.

PNEUMATIC HORSE-COLLAR.

SPECIFICATION forming part of Letters Patent No. 761,989, dated June 7, 1904.

Application filed August 1, 1903. Serial No. 187,809. (No model.)

To all whom it may concern:

Be it known that I, WILLIAM OST, a citizen of the United States, residing at Newark, in the county of Essex and State of New Jersey, have invented and produced a new and original Improvement in Pneumatic Horse-Collars; and I do hereby declare the following to be a full, clear, and exact description of the invention, such as will enable others skilled in the art to which it appertains to make and use the same, reference being had to the accompanying drawings, and to numerals of reference marked thereon, which form a part of this specification.

15 The objects of this invention are to secure greater comfort for horses or other draft-animals while drawing their loads, to enable the pneumatic sac within the collar to be more readily removed therefrom for the purpose of repair, inflating, or other purposes, to reduce the cost of construction, and to secure other advantages and results, some of which may be referred to hereinafter in connection with the description of the working parts.

20 The invention consists in the improved pneumatic horse-collar and in the arrangements and combinations of parts of the same, all substantially as will be hereinafter set forth and finally embraced in the clauses of the claim.

25 Referring to the accompanying drawings, in which like numerals of reference indicate corresponding parts in each of the several figures, Figure 1 is a front elevation of the improved collar. Fig. 2 is a side elevation of the same. Fig. 3 is a section, on an enlarged scale, taken on line α of Fig. 1; and Fig. 4 is a reduced detailed elevation of the pneumatic sac as preferably employed.

30 In said drawings, 10 and 11 indicate the sac-inclosing flaps, which when completely joined at their opposite edges, if in two pieces or more, form an approximately tubular casing. At the fore-wale or rib 121 said flaps are permanently joined together. They are also joined, preferably by the same stitching, to the fore-wale 121 and to an outer flap 13; but at their rearward or outer edges the said flaps 10 11 are perforated and provided with a series of eyelets, through which a cord or lac-

ing-thong 12 may be inserted to hold the said edges together. The said perforated edges extend, preferably, entirely around the collar, and when the said edges are unlaced a removal of the pneumatic sac 14 is readily permitted. At the outer forward side of the collar the said sac-inclosing flaps 10 11 are covered at the laced joint by the said flap 13, which is preferably given a higher finish, and thus is more or less ornamental to give a pleasing appearance to the eye. Said outer flap 13 being joined or fastened to the inner flap 11 and to the fore-wale at a distance from the lacing-joint, it is obvious that when it is found desirable to remove the flexible sac 14 hereinafter referred to access to the lacing cords or thongs can be gained with greater ease, and yet when in use the laced joint is entirely covered and concealed by said ornamental outer flap 13, which extends from the fore-wale, to which it is stitched, laterally outward, the free edge distant from the stitching lying over said joint and free to permit the fingers to enter between.

35 Within the casing 10 11 is arranged the sac 14, which is of flexible fabric or material impervious to air, the same being preferably of rubber or other material impervious to both moisture and air. The said parts are all suitably shaped to secure a proper receptacle for the sac and to properly fit the animal's neck and comfortably serve the purposes of a collar. The said sac is provided with a valve or inlet 15, of any ordinary construction, through which the air may be forced and retained when inflating the said sac.

40 I am aware that various modifications may be made in the construction of the collar. For example, the sac may be in sections corresponding with a similar construction of the collar, and the shape and detail construction of the collar may be varied to suit the various styles and patterns now common in the market.

Having thus described the invention, what I claim as new is—

45 1. The improved horse-collar herein described comprising a fore-wale, and two flaps stitched thereto, said flaps having their free edges opposite those stitched to the fore-wale perforated to receive a lacing cord or thong, 100

a lacing-cord joining said free edges of said flaps, a wide covering flap also stitched to the fore-wale and at its free edge extending over the laced joint or seam, the said flap being free 5 to be raised and permit unlacing of the first-said flaps, and a removable pneumatic sac incased in said laced flaps, substantially as set forth.

2. The improved horse-collar, comprising a 10 casing, the flaps of which are permanently joined at the fore-wale of said collar and are perforated at their free edges lying at the outer rearward sides of the collar, a pneu-

matic sac lying within said casing, a lacing-thong, and an outer flap permanently attached 15 to the collar at the fore-wale and extending backward and over the laced edges of the sac, substantially as set forth.

In testimony that I claim the foregoing I have hereunto set my hand this 23d day of 20 July, 1903.

WILLIAM OST.
